UNITED STATES PATENT OFFICE.

SPRAGUE F. HASKELL, OF ST. LOUIS, MISSOURI, ASSIGNOR TO THE INTERNATIONAL METAL WEATHER STRIP COMPANY, OF ST. LOUIS, MISSOURI.

WEATHER-STRIP.

971,374.

Specification of Letters Patent. Patented Sept. 27, 1910.

Application filed January 3, 1910. Serial No. 536,158.

To all whom it may concern:

Be it known that I, SPRAGUE F. HASKELL, a citizen of the United States, residing at the city of St. Louis, State of Missouri, have 5 invented certain new and useful Improvements in Weather-Strips, of which the following is a specification, reference being had therein to the accompanying drawings.

This invention consists of certain novel 10 improvements on the weather-strips disclosed in United States Letters-Patent No. 926,409, granted June 29, 1909, and has for its object to overcome certain important practical objections to, and defects in, the 15 weather-strips of that patent.

In the drawings forming part of this specification, in which like numbers of reference denote like parts wherever they occur, Fig. 1 is an elevation showing a door and sill having this invention applied thereto; 20 Fig. 2 is a plan view of the door sill; Fig. 3 is a perspective view of the metal threshold; Fig. 4 is a perspective view showing one end of the sill and a part of the door; Fig. 5 is 25 a sectional view on the line 5—5, Fig. 1; Fig. 6 is a sectional view on the line 6—6, Fig. 1; Fig. 7 is a perspective view of the plate which is designed to be secured to the free edge of the door; and Figs. 8, 9, 10, and 30 11 show alternate forms of the invention.

The door 1 is located in the frame 2 and above the sill 3. The inner and outer longitudinal edges of the sill 3 are preferably beveled, said inner edge being beveled 35 deeper than the outer edge to form a recess 4 in its upper surface.

The metal tread or wear-plate 5, which may be made of bronze, brass, or the like, is secured by screws 6 or other suitable 40 means to sill 3 and extends from end to end thereof, said plate projecting over the recess 4, each of its edges being beveled or rounded. The bevel of the outer edge of plate 5 preferably registers in the plane of the bevel of the outer edge of sill 3, and for this reason water that runs off plate 5 will 45 not flow between said plate and sill 3 and cause said sill to rot, but will flow down said outer beveled edges of plate 5 and sill 3. 50 The upper surface of said plate is corrugated or roughened, as indicated at 7, except at the end portions, where the upper surface is plain. A beveled surface 8 is provided at one end of said plate and is located adjacent the hinged edge of the door 55

1, and an inclined surface 9 is formed at the other end of said plate.

A metal strip 10, the edge 11 of which is bent, extends along the bottom of door 1 and is fastened thereto by screws 12 or by other suitable means. The edge 11 projects underneath door 1 and, when said door is closed, said edge enters recess 4 and underlies the inner edge of plate 5 in the manner best seen in Figs. 5 and 6. A plate 13 having a beveled edge 14 is fastened to the hinged edge of the door and occupies such position relative to the beveled surface 8 on plate 5 that, when the door 1 is closed, the beveled edge 14 rests upon the beveled surface 8 of the plate 5. A plate 15, which is provided with an inclined edge 16, is attached to the lock edge of the door 1, and, when said door is closed, the inclined edge 16 rests upon the inclined surface 9 of the plate 5. When the door 1 is being closed the edge 11 of strip 10 enters the recess 4 in the manner hereinabove described, and the beveled edge 14 of plate 13 and the inclined edge 16 of plate 15 slide upwardly on the beveled surface 8 and the inclined surface 9, respectively, thereby slightly raising the door 1 and causing the edge 11 to press snugly against the lower surface of the inner edge of plate 5, and thus preventing air or dust from passing under the door.

In this improved form of weather-strip the necessity of providing a felt strip in recess 4 is obviated, and the construction of strip 10 is greatly simplified and, also, the cost of manufacturing same is reduced, for the reason that it is only necessary to bend one edge of strip 10 and fasten same to one surface of the door, instead of forming a plate and attaching same to two surfaces of the door in the manner disclosed in my above-mentioned former patent.

In the device of my above-mentioned former patent, when the projection therein designated as 19 on plate 16 rides upon the bevel 6 of plate 5 to raise the door while same is being closed, a crack which allows the passage of air or dust beneath the door is left between edge 17 and the upper surface of plate 5, and it is one of the principal objects of the present invention to obviate that objection, by means of the close coöperation of the parts designated in this application as the inclined edge 16 of plate 15 with the inclined surface 9 of plate 5, 105 110

whereby no crack is left to allow air or dust to pass underneath the lock edge of the door in the closed position. Similarly, close co-operation of the beveled edge 14 of plate 13 with the beveled surface 8 of plate 5 prevents the passage of air or dust beneath the hinged edge of the door in the closed position.

In the alternative form depicted in Figs. 10 and 9, the metal plate 5 is omitted, and the metal plate 17 is substituted therefor. Said plate 17 is provided with a tread portion 18 and, also, with a folded lip 19 which extends underneath said tread portion and which preferably inclines downwardly from said tread portion. A projection 20 on the under fold of lip 19 is arranged to rest upon sill 3 and, also, to support the lip and tread portion, whereby the weight of the person or persons standing upon said tread portion is prevented from bending same.

The sill 3 is divided longitudinally at 21 and the vertical portion of plate 17 is inserted between the two parts of the sill, screws or other suitable means being used to fasten said plate in place. When said plate 17 is inserted between the parts of sill 3, in the manner just described, the top surface of the tread portion registers in the same plane with the top surface of one part of said sill, and projection 20 rests, in the manner hereinabove described, upon a recess portion 4 formed in the other part of said sill. A plate 22 having a beveled surface 8 may be secured to one end of plate 17 and a similar plate (not shown in the drawings), having an inclined surface like the groove 9 in Figs. 2, 3, and 6, may be secured to the other end of said plate 17. When the door 1 is closed, the edge 11 of plate 10 enters recess 4 and fits snugly against the inclined surface of the under fold of lip 19, thereby preventing the passage of air or dust beneath the door.

In Figs. 10 and 11, another form of tread or wear-plate is shown, and with same (when the sill has become worn or is not high enough) may be used a filler 23 preferably of wood, supported by sill 3, the outer longitudinal edge thereof being beveled to align with the bevel of said sill. The wear-plate 24 rests upon filler 23 (or, when that is omitted, upon sill 3), and is fastened thereto by screws 25 or other suitable means, which, also, secure filler 23 to sill 3. The outer longitudinal edge of plate 24 is bent so that it will be supported by the beveled edge of said filler, and is tapered in order to prevent stumbling by those passing over it. Said outer edge of plate 24 preferably overlaps the crack between filler 23 and sill 3, and thereby prevents water from flowing into said crack. The inner longitudinal edge is bent to form a beveled surface 26 and is, also, bent again to form a lip 19 having a

projection 20. Said projection 20 rests upon sill 3 and supports lip 19 and beveled surface 26, and, also, prevents the weight of a person or persons standing upon said beveled surface from bending said beveled edge. Due to the fact that the inner edge of plate 24 is reinforced by bending same to double the thickness thereof and, also, because it is supported by projection 20, a thinner wear-plate 24 can be used in this form of the device than when the inner edge of the wear-plate projects straight over recess 4.

In my above-mentioned former patent the projection therein designated as 19 is adapted to raise the door only from the lock edge; but in the present device the door is raised equally from the hinge edge and the lock edge, thus producing complete contact between edge 11 and the under surface of tread 5, this being due to the provision of the cam members 8 and 14 at one edge of the door and of cam members 9 and 16 at the other edge thereof, and this is true, also, of the alternative forms shown in Figs. 8, 9, 10, and 11.

I claim:

1. In an interlocking threshold, the combination of a recessed sill having an inclined slideway extending across one end thereof approximately the thickness of the door, an interlocking member adapted to enter said recess, and a member borne by the door having an inclined edge extending from end to end and so sloped as to conform to and co-operate with said inclined slideway throughout its entire extent, for producing an air tight joint between said edge and the adjacent surface of said slideway.

2. In an interlocking threshold, the combination of a sill containing a recess, a member carried by the door adapted to enter same, said sill having a beveled portion extending transversely at one end thereof, and a beveled member borne by the door extending transversely of same and adapted to engage said beveled portion of said sill throughout its entire extent, for producing an air tight joint between the contacting surfaces of said beveled portion and beveled member.

3. In an interlocking threshold, the combination of a sill containing a recess, a member carried by the door adapted to enter same, said sill having at each end thereof a beveled surface extending transversely of same, and a pair of beveled members borne by the door arranged to engage said transverse beveled surfaces on the sill for raising the door equally from both longitudinal edges, to produce complete contact of the first-named member in said recess.

4. In an interlocking threshold, the combination of a sill having a recess, a member so arranged upon the door as to enter said recess when the door is closed, said sill hav-

- ing at one end a transversely-extending cam groove and at the other a transversely-extending cam surface, a cam member borne by said door and adapted to ride in said groove and tightly engage same, and another cam member borne by said door and adapted to ride upon said cam surface at the other end of the sill and tightly to engage same for producing air tight joints between the cam members and said cam groove and cam surface, and for raising the door equally from both longitudinal edges, to produce complete contact of the first-named member in said recess.
5. A weather-strip comprising a sill having a recessed portion, a tread plate secured to said sill and arranged to project over said recessed portion, a pendent member carried by the door and having its lower edge adapted to underlie the projecting edge of said tread plate when the door is closed, one end of said tread plate being provided with a transversely arranged beveled surface extending completely thereacross, and a plate borne by the door and having a beveled edge, the beveled edge of said plate being adapted to engage the beveled surface of said tread plate and to raise the door while the door is being closed, whereby an air tight joint is produced between said edge and surface, and whereby the lower edge of said member is caused to press against the lower surface of the projecting edge of said tread plate.
10. A weather-strip comprising a sill having a recessed portion, a tread plate secured to said sill and arranged to project over said recessed portion, a pendent member carried by the door and having its lower edge adapted to underlie the projecting edge of said tread plate when the door is closed, one end of said tread plate being provided with a transversely arranged beveled surface extending completely thereacross, and a plate borne by the door and having a beveled edge, the beveled edge of said plate being adapted to engage the beveled surface of said tread plate and to raise the door while the door is being closed, whereby an air tight joint is produced between said edge and surface, and whereby the lower edge of said member is caused to press against the lower surface of the projecting edge of said tread plate.
15. A weather-strip comprising a sill having a recessed portion, a tread plate secured to said sill and arranged to project over said recessed portion, a pendent member carried by the door and having its lower edge adapted to underlie the projecting edge of said tread plate when the door is closed, one end of said tread plate being provided with a transversely arranged beveled surface extending completely thereacross, and a plate borne by the door and having a beveled edge, the beveled edge of said plate being adapted to engage the beveled surface of said tread plate and to raise the door while the door is being closed, whereby an air tight joint is produced between said edge and surface, and whereby the lower edge of said member is caused to press against the lower surface of the projecting edge of said tread plate.
20. A weather-strip comprising a sill having a recessed portion, a tread plate secured to said sill and arranged to project over said recessed portion, a pendent member carried by the door and having its lower edge adapted to underlie the projecting edge of said tread plate when the door is closed, one end of said tread plate being provided with a transversely arranged beveled surface extending completely thereacross, and a plate borne by the door and having a beveled edge, the beveled edge of said plate being adapted to engage the beveled surface of said tread plate and to raise the door while the door is being closed, whereby an air tight joint is produced between said edge and surface, and whereby the lower edge of said member is caused to press against the lower surface of the projecting edge of said tread plate.
25. A weather-strip comprising a sill having a recessed portion, a tread plate secured to said sill and arranged to project over said recessed portion, a pendent member carried by the door and having its lower edge adapted to underlie the projecting edge of said tread plate when the door is closed, one end of said tread plate being provided with a transversely arranged beveled surface extending completely thereacross, and a plate borne by the door and having a beveled edge, the beveled edge of said plate being adapted to engage the beveled surface of said tread plate and to raise the door while the door is being closed, whereby an air tight joint is produced between said edge and surface, and whereby the lower edge of said member is caused to press against the lower surface of the projecting edge of said tread plate.
30. A weather-strip comprising a sill having a recessed portion, a tread plate secured to said sill and arranged to project over said recessed portion, a pendent member carried by the door and having its lower edge adapted to underlie the projecting edge of said tread plate when the door is closed, one end of said tread plate being provided with a transversely arranged beveled surface extending completely thereacross, and a plate borne by the door and having a beveled edge, the beveled edge of said plate being adapted to engage the beveled surface of said tread plate and to raise the door while the door is being closed, whereby an air tight joint is produced between said edge and surface, and whereby the lower edge of said member is caused to press against the lower surface of the projecting edge of said tread plate.
35. A weather-strip comprising a sill having a recessed portion, a tread plate secured to said sill and arranged to project over said recessed portion, a pendent member carried by the door and having its lower edge adapted to underlie the projecting edge of said tread plate when the door is closed, one end of said tread plate being provided with a transversely arranged beveled surface extending completely thereacross, and a plate borne by the door and having a beveled edge, the beveled edge of said plate being adapted to engage the beveled surface of said tread plate and to raise the door while the door is being closed, whereby an air tight joint is produced between said edge and surface, and whereby the lower edge of said member is caused to press against the lower surface of the projecting edge of said tread plate.
40. A weather-strip comprising a sill having a recessed portion, a tread plate secured to said sill and arranged to project over said recessed portion, a pendent member carried by the door and having its lower edge adapted to underlie the projecting edge of said tread plate when the door is closed, one end of said tread plate being provided with a transversely arranged beveled surface extending completely thereacross, and a plate borne by the door and having a beveled edge, the beveled edge of said plate being adapted to engage the beveled surface of said tread plate and to raise the door while the door is being closed, whereby an air tight joint is produced between said edge and surface, and whereby the lower edge of said member is caused to press against the lower surface of the projecting edge of said tread plate.
45. A weather-strip comprising a sill having a recessed portion, a tread plate secured to said sill and arranged to project over said recessed portion, a pendent member carried by the door and having its lower edge adapted to underlie the projecting edge of said tread plate when the door is closed, one end of said tread plate being provided with a transversely arranged beveled surface extending completely thereacross, and a plate borne by the door and having a beveled edge, the beveled edge of said plate being adapted to engage the beveled surface of said tread plate and to raise the door while the door is being closed, whereby an air tight joint is produced between said edge and surface, and whereby the lower edge of said member is caused to press against the lower surface of the projecting edge of said tread plate.
50. A weather-strip comprising a sill having a recessed portion, a tread plate secured to said sill and arranged to project over said recessed portion, a pendent member carried by the door and having its lower edge adapted to underlie the projecting edge of said tread plate when the door is closed, one end of said tread plate being provided with a transversely arranged beveled surface extending completely thereacross, and a plate borne by the door and having a beveled edge, the beveled edge of said plate being adapted to engage the beveled surface of said tread plate and to raise the door while the door is being closed, whereby an air tight joint is produced between said edge and surface, and whereby the lower edge of said member is caused to press against the lower surface of the projecting edge of said tread plate.
- face, and whereby the lower edge of said member is caused to press against the lower surface of the projecting edge of said tread plate.
7. A weather-strip comprising a sill having a recessed portion, a tread plate secured to said sill and arranged to project over said recessed portion, a pendent member carried by the door and having its lower edge adapted to underlie the projecting edge of said tread plate when the door is closed, said tread plate being provided with a transversely arranged beveled surface adjacent the hinged edge of the door and with a transversely arranged inclined surface adjacent the lock edge of the door, a plate having a beveled edge secured to the hinged edge of the door, and a plate having an inclined edge secured to the lock edge of the door, beveled and inclined edges of said plates being adapted to engage the beveled surface and the inclined surface, respectively, of said tread plate to raise the door equally from both edges while being closed, to produce complete contact of the lower edge of said pendent member with the lower surface of the projecting edge of said tread plate.
8. The combination with a door sill having an overhanging longitudinal lip at one edge thereof and a member carried by the door at the bottom thereof, the member having an inwardly bent portion which in the closed position of the door engages under the lip in contacting relation with the under surface thereof throughout its entire extent, of cam faced members secured at the lower ends of the two edge faces of the door inwardly of the lip, and means provided at both ends of the sill to engage the cam faced members when the door is being closed and, by virtue of such engagement, to produce a raising of the door sufficient to establish the contacting relation of said inwardly bent portion and the under face of the lip.
